RAILWAY SIGNALING SYSTEM

Frank H. Richterkessing, Louisville, Ky., assignor to Nachod & United States Signal Co., Inc., Louisville, Ky., a corporation of New York

Application January 20, 1932, Serial No. 537,687

31 Claims. (Cl. 246—37)

My invention relates to improvements in railway signaling systems especially those adapted to control car or train movements upon a railway, and more particularly upon an electric railway.

The main object of my invention is to provide a signal system in which the moving train is adapted to automatically close the electric control circuits through the axle and wheels thereof.

Another object of my invention is to provide a signaling system for railways on which the cars or trains travel in one direction only, as for example in a double track railway, the system providing stop, caution and proceed indications, or all of them.

A further object of my invention is to provide a system in which failures in the circuits or apparatus will cause a minimum of danger to the traffic operating thereon. A still further object of my invention is to provide a system in which a train upon leaving a block will not restore that block to normal until the control apparatus for the successive block which the train is entering has been properly operated.

A still further object of my invention is to provide an indication which shall be visible to the operator of the train, and which will indicate the proper operation of the control relays when the train enters a block.

A still further object of my invention is to provide a system which is operated through insulated rail sections and which will retain the maximum protection for a train within the signaling block although the train has become derailed and its wheels removed from the running rails.

A still further desired result effected by my invention is the employment of a comparatively low voltage for the apparatus connected to the insulated rail sections and a higher voltage for the other control apparatus involving line wire control.

A still further desired result effected by my invention is the disposition of the short insulated sections, such that the system is applicable to railways within paved streets, and which will not be affected by vehicles other than trains operating on the running rails.

A still further desired result effected by my invention is its application within locations where it is necessary to employ the conventional type of continuous rail circuit to control other forms of signaling.

A still further desired result embodied in my invention is the employment of apparatus which

will not be affected by intermittent interruptions of the controlling power.

My invention further consists of certain novel constructions and characteristics which are fully disclosed in the following description and accompanying drawings in illustration thereof; in which—

Figure 1 is a diagrammatic drawing showing the manner in which the control relay of my invention is connected to the short insulated rail sections.

Figure 2 is a modification of Figure 1 indicating the manner in which the control apparatus is connected to the short insulated rail sections when the control is located within continuous rail signaled territory.

Figure 3 is a further modification of Figure 2 in which one insulated rail section is employed rather than the two sections indicated in Figures 1 and 2.

Figure 4 is a diagrammatic representation of my complete invention showing three successive signal blocks, with the train traveling within the third block.

With further reference to Fig. 4 the characters RR and RR₁ designate the running rails of a railway system, and it is obvious to those skilled in the art that the rails may be those of an electric railway system utilizing the rails as a conductor for the return propulsion current of the train traveling thereon or for trains which are operated by other methods. It will be further noted that signal indications are located at the entrance of each block, and short insulated sections are located adjacent the signals. For the first block, signal indications R₂, Y₂ and G₂ are employed to indicate to a train the condition of the block extending beyond the signal, and the insulated sections X and X₁ are employed to control the indication R₂ for indicating the occupied condition of block 1 when a train operates thereover. In block 2 signal indications R₁, Y₁, and G₁ are similarly employed, and the insulated sections X₂ and X₃ are utilized in controlling the indication R₁ for showing the occupied condition of block 2. Similarly, indications R and G are employed for block 3 with insulated sections X₄ and X₅ controlling the indication R for indicating the occupied condition of block 3. At the extremity of block 3 insulated sections X₆ and X₇ are so located that a train leaving the signaled territory will restore the system to normal. With further reference to the signal indications of the system, normally with each signal block unoccupied, a green in-

55

dition will be displayed at the entrance of each respective block, namely signals G2, G1 and G. As a train enters a block it will change the indication at the entrance of the block the train 5 has entered from normal green to red. For instance a train entering the first block will set up red signal R2 in the rear of it, and will receive the white pilot WL2 to indicate that the control has been properly operated. Upon leaving block 1 and entering block 2 it will likewise 10 change the normal green indication G1 of block 2 to red R1, and receive the white pilot WL1 indicating the proper operation of the control apparatus of block 2. Instant to this operation 15 it will change the red signal of block 1 to caution or yellow which is designated by the character Y2. As the train proceeds and enters block 3, as illustrated in Fig. 4, the normal green indication for block 3 will be changed to red R and 20 instant to this operation the indications of block 2 will be changed from red to yellow Y1 and the indications of block 1 will be changed from yellow to green G2. As the train leaves the signaled territory and engages insulated sections 25 X6 and X1 the normal green indications G1 and G will be restored for their respective blocks.

In the signal control apparatus I employ transformers T2, T1, T and T3 for reducing the higher line voltage to a comparatively low voltage for 30 the operation of the track control relays of each block. In block 1 the characters L2 represent a novel form of latch or locking relay employed in my invention and embraces each of the operating coils C9 and C8. The two operating coils 35 C9 and C8 are placed in a definite relation to each other and in such a manner that they will operate a mechanical locking device LO2 placed therebetween. When the operating coil C8 is energized and raises its armatures, the armatures 40 will be mechanically held in the raised position by locking arm LO2, and when the operating coil C9 is energized and raises its respective armature the locking arm LO2 will be moved out of locking engagement with the armatures of the 45 operating coil C8, thereby permitting the latter armatures to be brought into engagement with their respective back contacts. It is believed that a further detailed discussion of the operation 50 and construction of this relay is unnecessary, since it will be obvious to those skilled in the art how such a relay may be constructed to perform in the manner designated. In blocks 2 and 3 the characters L1 and L designate a similar relay employed for their respective blocks.

55 I also employ relays M2 and M1 for controlling the display of the yellow and green indications of their respective blocks. The conventional track type relay designated by the character E is employed for energizing the line wire 40 for restoring the third block to normal. With further reference to the transformers T2, T1 and T, it will be noted that the primary windings of these 60 transformers are of the conventional auto-transformer construction. The purpose of such an arrangement is to provide a low voltage for the operation of the signal lamps, which in practice will enable the use of a small lamp which has a greater degree of filament concentration, thereby permitting the light source to be located 65 nearer the theoretical center of the optical system.

In each of the drawings accompanying the specification, like numerals and characters have been employed to designate identical or similar parts. It is, therefore, believed that lengthy de-

scriptions of each of the figures are unnecessary since the teachings of one description may be applied to the remaining figures.

With further reference to Figure 1 it will be noted that the parts embracing the track circuit control are diagrammatically represented as having the wheels of the train in contact engagement with the short insulated sections. Inasmuch as each of the circuits embracing the short insulated sections are identical, the end clearing control embodying the relay E has been selected for describing the path of the electrical circuits. Fig. 1 illustrates the circuits of relay E in detail. With the wheels of the train in the position as indicated in Fig. 1, an electrical circuit will be established for the energization of the operating coil C6 of relay E. The latter circuit is completed from the secondary S3 of track transformer T3, through wire 45 to insulated section X7, through wheel W3, axle AX1, wheel W2 to 20 the running rail RR1, through the bond wire 62 to the running rail RR, through wheel W, axle AX, wheel W1 to the insulated section X6, wire 43, winding C6 and wire 44 to the other secondary terminal of transformer T3. The energization 25 of operating coil C6 will bring the armature AE of relay E into contact engagement with its front contact 41 thereby establishing a circuit from the BX power terminal, through wire 42, through the armature AE, front contact 41, to wire 40. 30 It is obvious that the connecting of line wire 40 to the BX power terminal will pass operating current through the magnet C5 of locking relay L appearing in Fig. 4.

With reference to Fig. 4 it will be noted that the operating coil C1 of the locking relay L1 is connected to the insulated sections X2 and X3 in the same manner as illustrated in Fig. 1, and the circuit further includes the secondary S' of the track transformer T1 for supplying the operating 40 current in this circuit. It will likewise be noted that the operating coil C4 of the locking relay L is connected to the insulated sections X4 and X5 in a similar manner with the secondary S of transformer T included in this circuit for supplying 45 the operating current therein.

We will now assume the train as occupying the second block of the system and preparing to enter the third block of the system. Instant to the engagement of the wheels of the train with the 50 insulated sections X4 and X5, the coil C4 of the locking relay L will be energized and its armature 76 will be brought into contact engagement with its front contact 22, and instant to this operation the locking lever LO will be engaged 55 and moved out of mechanical engagement with the armatures 77 and 78 associated with the operating coil C5 of the locking relay L. This operation will result in the armatures 77 and 78 disengaging their respective front contacts and coming into contact engagement with their respective back contacts as illustrated in Fig. 4. It will be further noted that when the armature 78 engages its back contact 24 a circuit will be established 60 from the BX power terminal, through wire 25, armature 78, back contact 24, wire 23, front contact 22, armature 76 associated with relay coil C4, line wire 21, operating coil C2 of locking relay L1, wire 7, wire 9 to the other power terminal CX. The completing of this electrical circuit as 65 described and the subsequent energization of the operating coil C2 will result in the armatures A2 and AL2 of the locking relay L1 being raised into their normal mechanical latched position as illustrated. 70

As soon as the wheels of the train disengage the insulated sections **X4** and **X5** and advance to the position illustrated in Fig. 4 the signal indications will be changed so as to display green 5 for the first block, yellow for the second block, and red for the third or occupied block. The circuit governing the display of the red indication for the third block is completed from the intermediate voltage tap **79** of the auto-primary **P1** of 10 transformer **T1**. It will be further obvious that, as the train advances and engages the sections **X6** and **X7**, as described for Fig. 1, the line wire **40** will be energized through the engagement of armature **AE** with its front contact **41**, the latter 15 mentioned circuit being completed from the **BX** power terminal, through wire **42**, armature **AE** of relay **E**, front contact **41** of relay **E**, wire **40**, operating coil **C5** of relay **L**, wire **39**, wire **38** to the other power terminal **CX**. It will also be obvious 20 that when the latter mentioned circuit is completed, and with the resulting energization of the operating coil **C5**, the armatures **77** and **78** will be brought out of contact engagement with their respective back contacts and into contact 25 engagement with their respective front contacts, and instant to this operation the locking lever **LO** will mechanically engage the latter mentioned armatures and mechanically retain them in their raised position.

30 There are seven circuits embodied in the operation of one complete block equipment and for clarity of description each of these will be entitled in accordance with their function and described individually, all of the circuits being described as 35 embracing the apparatus for signal block **2**.

The system illustrated in Fig. 4 is a typical three block installation, in which the relay apparatus has been assembled in accordance with the circuit requirements of each block. The relays 40 and circuit wiring for the control of the signals for blocks **1** and **2** are identical, while the relays and circuit wiring for controlling the signal for block **3** comprises only a part of the equipment of a complete block. It will be obvious to those 45 familiar with the art that such an expedient merely employs the controls necessary to produce the desired operations.

*First—Current supply circuit for primary **P1** of transformer **T1**.*—This circuit is completed 50 from power terminal **BX**, through wire **4**, wire **5** to primary **P1**, from the other terminal of primary **P1**, through wire **6**, wire **9** to the other power terminal **CX**.

Second—The normal clear or green signal circuit.—It will be noted that the latter circuit will 55 require that both armatures **A2** and **AM1** of relays **L1** and **M1** respectively be in their raised positions, and that the circuit will be completed from the intermediate power terminal **20** of the auto-primary **P1** of transformer **T1**, through the armature **A2** of relay **L1**, front contact **14**, wire **15**, armature **AM1** of relay **M1**, front contact **48**, wire **49**, green signal lamp **G1**, wire **19** which is the return intermediate power terminal to the auto-primary **P1** of transformer **T1**.

Third—The caution or yellow signal lamp circuit.—It will be noted that it is required for the completion of this circuit that the armature **A2** of relay **L1** be raised and the armature **AM1** of relay **M1** be in engagement with its back contact **16**, and that the circuit will be completed from the intermediate power terminal **20** of the auto-primary **P1** of transformer **T1**, through the armature **A2** of relay **L1**, front contact **14**, wire **15**, armature **AM1** of relay **M1**, back contact **16**, wire **17**,

yellow signal lamp **Y1**, wire **18**, wire **19**, which is the return power terminal to the auto-primary **P1** of transformer **T1**.

Fourth—The red or stop indication for indicating an occupied block.—It will be likewise noted that it is necessary only for armature **A2** of relay **L1** to be in engagement with its back contact **13** to establish this circuit, and that the circuit will be completed from the intermediate power terminal **20** of the auto-primary **P1** 10 of transformer **T1**, through the armature **A2** of relay **L1**, back contact **13**, wire **12**, red signal lamp **R1**, wire **11**, white train indicator lamp **WL1**, wire **10** to the power terminal **CX** which is a common terminal to the auto-primary **P1** of 15 transformer **T1**.

*Fifth—Hold clear circuit embracing the relay **M1**.*—It will be noted that it is necessary that the armature **78** of locking relay **L** be in engagement with its front contact **47** for the completion 20 of this circuit. With this condition a circuit will be established from the **BX** power terminal, through wire **25**, armature **78** of relay **L**, front contact **47** of relay **L**, wire **46**, operating coil **C3** of relay **M1**, wire **8**, wire **9** to the other 25 power terminal **CX**.

Sixth—Clearing control circuit.—It will be noted that in order to establish the clearing control circuit the armature **76** of relay **L** must be in engagement with its front contact **22**, and the 30 armatures associated with the operating coil **C5** of relay **L** be in contact engagement with their back contacts. When these conditions exist a circuit will be established from the **BX** power terminal, through wire **25**, armature **78** of relay **35** **L**, back contact **24**, wire **23**, front contact **22**, armature **76**, line wire **21**, operating coil **C2** of relay **L1**, wire **7**, wire **9** to the other power terminal **CX**.

Seventh—Track control circuit.—It will be 40 noted that in order for this circuit to be established the wheels of the train must be in engagement with the insulated rail sections **X2** and **X3**. A circuit will then be established from the secondary **S1** of transformer **T1**, through wire **3** 45 to the insulated section **X2**, through wheel **W1**, axle **AX**, wheel **W** to the running rail **RR**, through the bond wire **55** to the running rail **RR1**, through wheel **W2**, axle **AX1**, wheel **W3** to the insulated section **X3**, through wire **1**, operating coil **C1** of locking relay **L1**, wire **2** to the other terminal of the secondary **S1** of transformer **T1**.

Fig. 2 illustrates a preferred manner of connecting the control apparatus to short insulated 55 rail sections when the control is located within continuous rail signaling territory. In the figure, the characters **RR** and **RR1** designate the running rails for an electric railway car. The characters **BS** designate a conventional semaphore signal controlled by a conventional continuous rail track circuit. It will be apparent to those familiar with the art that the track relay **BR** will receive its operating current from the secondary **SB** of transformer **TB** through the 60 rails **RR** and **RR1**, but when a car or train occupies the rails, between the transformer connections and relay connections, the relay will be deprived of operating current thereby releasing its armature. Since the rails carry the return 65 D. C. propulsion current for the car or train, some method is usually employed to form the continuous D. C. connection between the various blocks. In the figure impedance bonds **B** have been shown for this purpose. It is well known 70 75

to those familiar with the art, that such devices have a very low ohmic resistance and permit the heavy D. C. currents to readily flow therethrough. Likewise, the impedance bond has a high impedance to alternating currents ordinarily employed for signaling purposes, thereby preventing the signal current from flowing to the neighboring block section. It will be apparent that if the insulated rail sections X6 and X7 of applicant's system, were placed in opposite rails, serious interference would be encountered with the existing conventional continuous rail track circuits, since an auxiliary current would be fed to the rails in the event the insulation for insulated rails X6 and X7 became "broken down". To prevent such a condition it is proposed that the insulated sections X6 and X7 be installed in the same rail thereby making it impossible to super-impose an auxiliary feed to the track circuit relay BR.

The semaphore signal BS is represented by a conventional symbol which will be readily identified by those familiar with the art of railway signaling. Such a signal consists of a movable arm or blade projecting from a pipe standard or suitable mounting, and is interpreted as giving a "stop" indication when the blade is in the horizontal position. When the blade is moved to a position making an angle of 45 degrees to the horizontal position, it is interpreted as displaying a "caution" indication. Usually, a motor is employed to drive a gear train for moving the blade to the 45 degree position, with a latching magnet operable to retain the blade in its operated position. It is apparent therefore, that this type of semaphore signal requires power to move the blade from the "stop" position to the "caution" position. To restore the blade to the "stop" position, the operating current is removed from the latching magnet, thereby permitting the semaphore blade to be moved to its "stop" position by gravity. In Fig. 2 the characters BS specifically refer to a two-position semaphore signal, that is, one which will be moved from the horizontal or "stop" position to the 45 degree or "caution" position when current is supplied to its operating motor and latching magnet through wire 70. If the armature ABR of relay BR is released, operating current will be discontinued in the circuit of the semaphore signal, and the blade will drop to the horizontal position by gravity. As is well known, many other forms of signaling devices are employed to denote the condition of signaled territory to train operators, such as color light signals, position light signals or a combination of same. Since the construction and operation of signal BS does not contribute to the operation of applicant's system, the signal BS may be regarded as a lamp energized when the circuit from wire 68 is completed through armature ABR, front contact 69, wire 70, through the signal lamp, wire 71 to the return of the line CX, to denote a clear or unoccupied block. When a train is in the block the armature ABR will release and discontinue current in this circuit, thereby discontinuing the signal lamp indication, denoting that the block is occupied. With further reference to Fig. 2 it will be noted that the primary PB of transformer TB receives energization current through wires 72 and 73, and that the low voltage supplied by the secondary SB is connected through wires 74 and 75 to the running rails RR and RRI. It will be evident that the rails RR and RRI form conductors for directing current to the wires 76 and 77 connecting the operating coil CBR of

relay BR. As is well known to those familiar with the art, the presence of a train on rails RR and RRI will shunt the current flow through the operating coil CBR thereby effecting the release of armature ABR.

Fig. 3 is identical to Fig. 2 with the exception that only one of the transformer terminals of transformer T3 is entirely insulated from the running rail RRI. It therefore is evident that it will be required that only one of the insulated joints 51 or 58 be short circuited in order to operate the signal relay E, while in Fig. 2 it will be required that at least one insulated joint for each of the insulated rails X6 and X7 be short circuited. It is believed that the similarity of Figs. 2 and 3 will be obvious to those familiar with the art, and that the operation of relay E is the same as described for Fig. 1.

While I have been specific in the arrangements and applications of the apparatus and circuits embraced in my invention, it is to be expected that many modifications may be resorted to without departing from the spirit and principle of my invention.

I claim:

1. In a signaling system, comprising similar signaling apparatus at each of a plurality of separate stations, said apparatus at one station comprising a vehicle controlled circuit, an electro-magnet controlled by the said circuit, a switch controlled by the said electro-magnet, a second electro-magnet and a plurality of switches controlled thereby, means associated with the first said switch for controlling the said plurality of switches, a third electro-magnet controlled by one of said plurality of switches at another station, and means at said one station for displaying one or another of said signals controlled by said second and third electro-magnets, and means for controlling the said second electro-magnet including the switches of the said first and second electro-magnet at the said another station.

2. The combination of a block or section of a railway, a plurality of insulated rail sections to be temporarily engaged by car or train, an electro-magnet controlled thereby, a switch controlled by the said electro-magnet, a second electro-magnet and a plurality of switches therefor being mechanically latched in one of their operating positions, a third electro-magnet and a switch controlled thereby, a signal, means controlled by said second and third electro-magnets for displaying the said signal, said first electro-magnet adapted for shifting the said plurality of switches of the said second electro-magnet upon the entry of a car or train into said block or section, a second signal, means displaying said second signal when the plurality of switches are shifted and discontinuing the display of the first said signal, a third signal, means responsive to the entry of a car or train into the block or section in advance of the first main block or section for energizing the said second electro-magnet and deenergizing the said third electro-magnet and means responsive to such altered conditions of said second and third electro-magnets for displaying said third signal.

3. In a signaling system adapted to be operated by a train, in combination with a track for the said train, said track comprising a plurality of insulated sections, of signal apparatus at a station comprising means for giving a plurality of signal indications, electro-magnets at the same station having independent magnetic circuits and normally cooperating to control the

- said means to give a clear or proceed indication, one of said electro-magnets being normally de-energized and adapted to be temporarily energized by a train or car engaging the said insulated sections to affect the said means to discontinue the said clear or proceed indication and to give another one of said signal indications, and signaling apparatus at another station comprising similar cooperating electro-magnets, and
- 5 10 15 20 25 30 35 40 45 50 55 60 65 70 75
- 10 a switch controlled by one of said last mentioned electro-magnets for controlling the second of first mentioned cooperating electro-magnets.
4. In a signaling system divided into a plurality of successive blocks and adapted to be operated by a train, in combination with a block or section of a railway and a track for the said train, said track comprising insulated sections at one of said stations, an electro-magnet adapted to be temporarily controlled by a train or car engaging the said insulated sections, a switch controlled by the said electro-magnet, a second switch, a normally indicating proceed signal controlled by the said second switch, a stop signal, and mechanical means cooperating with the said first and second switches whereby the first switch may control the second to discontinue the display of said proceed signal and cause the display of the said stop signal, and means responsive to the entry of the train into the successive block of the system, for restoring the said second switch to normal and to withhold the normal operation of the said proceed signal.
5. In a signaling system adapted to be operated by a train, in combination with a block or section of a railway and a track for the said train, said track comprising a plurality of insulated sections, an electro-magnet adapted to be temporarily controlled by a train or car engaging the said insulated sections, a switch controlled by the said magnet, a clear or proceed signal, second and third switches normally cooperating to display the said clear or proceed signal, mechanical means cooperating with the said first and second switches whereby the first switch may control the second to discontinue the display of said proceed signal, and signaling apparatus at another station comprising an automatically controlled switch, said third switch responsive to the operation of means controlled by the last mentioned switch to discontinue the display of the said proceed signal.
6. In a signaling system adapted to be operated by a train, in combination with a block or section of a railway and a track for the said train, said track comprising a plurality of insulated sections, an electro-magnet adapted to be energized by a train or car engaging the said insulated sections, a switch controlled by the said magnet, a clear or proceed signal, second and third switches normally cooperating to display the said clear or proceed signal, mechanical means cooperating with the said first and second switches whereby the first switch may control the second to discontinue the display of said proceed signal and cause the display of a stop signal, signaling apparatus at another station comprising an automatically controlled switch, operating means for the said third switch controlled by the said automatically controlled switch, and a third signal displayed in response to the normal condition of the said second switch and abnormal condition of said third switch.
7. In a signaling system adapted to be operated by a train, in combination with a block or section of a railway and a track for the said
- train, said track comprising insulated sections, an electro-magnet adapted to be energized by a train or car engaging the said insulated sections, a switch controlled by the said electro-magnet, a clear or proceed signal, second and third switches normally cooperating to display the said clear or proceed signal, a second signal, mechanical means cooperating with the said first and second switches whereby the first switch may control the second to discontinue the display of said proceed signal and cause the display of the said second signal, signaling apparatus at another station comprising an automatically controlled switch, the said second switch being normally held in its raised or actuated position by the said mechanical means, and the said third switch controlled by an electro-magnet normally energized through a circuit connecting the said automatically controlled switch at the another station.
8. In a signaling system adapted to be operated by a train, in combination with a block or section of a railway and a track for the said train, said track comprising a plurality of insulated sections, a signal, switches normally in their actuated positions cooperating to cause the display of the said signal, one of said switches being normally mechanically locked in its actuated position, a second signal, means controlled by the temporary engagement of a train with the said insulated sections upon entry of a train into said block or section for releasing the mechanical lock on the said one switch to permit the said switch to release from its actuated position and cause the display of said second signal and discontinue the display of the first said signal, a third signal, a normally energized electro-magnet for normally retaining one of the aforesaid switches in its actuated position, and a second electro-magnet for actuating the said one switch, means responsive to the entry of the train into block or section in advance of the first named block or section for de-energizing the first said electro-magnet and energizing the said second electro-magnet wherein the said second signal is discontinued and the third signal is established, and means responsive to the entry of the train into the block or section in advance of said second block or section to re-establish the display of the first said signal and discontinue the display of the third.
9. The combination with a pair of electro-magnets at the same station, of movable means respectively operated thereby, each of said movable means having two operable positions, one of said movable means being normally mechanically locked in one of its operable positions, a three indication signaling means controlled by the said movable means, the magnetic circuits of said electro-magnets being independent of each other, and vehicle controlled means for releasing the said mechanical lock to permit said one movable means to shift to its other operable position, and means for controlling the electro-magnet of the other said movable means, whereby said signal means may be caused to give any one of its three indications dependent upon the positions of the said movable means.
10. In a railway block signaling system, comprising a plurality of similar signal stations, an insulated rail section in the track rails at each block signaling station on each side of the track, an incomplete electric circuit connecting the said insulated rail sections including an electro-mag- 70 75

- net, a second electro-magnet and a switch therefor normally mechanically locked in its electrically operated position, a signal, means controlled by the said switch for establishing the 5 play of the said signal, a switch controlled by the first electro-magnet and adapted to release the lock and the switch of the said second electro-magnet upon the entry of a car or train into the said block or section, and means responsive to 10 the operation of the corresponding first and second switches at another station to temporarily energize the second electro-magnet to restore the first mentioned switch to its normally locked condition.
- 15 11. In a railway block signaling system comprising similar apparatus at a plurality of signal stations, an insulated rail section in each track rail at each block signaling station, an incomplete electric circuit connecting the said insulated rail sections including an electro-magnet, a second electro-magnet and a plurality of 20 switches therefor being mechanically latched in one of their operating positions, a third electro-magnet, a signal, means normally controlled by said second and third electro-magnets for governing the display of the said signal, said first electro-magnet adapted for shifting the said plurality of switches of the said second electro-magnet upon the entry of a car or train into the 25 said block or section, a second signal, means for displaying said second signal when the plurality of switches are shifted and for discontinuing the display of the first said signal, and means responsive to the operation of the first mentioned 30 electro-magnet at another station to temporarily energize the said second electro-magnet to restore the plurality of switches at the first mentioned station to normal, and means responsive to the condition of the plurality of switches at 35 the said another station for controlling the said third electro-magnet.
12. In a railway block signaling system, an insulated rail or rail section in the track rails at each block signaling station on each side of the 40 track, an incomplete electric circuit connecting the said insulated rail sections including an electro-magnet, a second electro-magnet and a plurality of switches therefor, being mechanically latched in one of their operating positions, a third electro-magnet, a signal, means controlled by said 45 second and third electro-magnets for governing the display of the said signal, said first electro-magnet adapted for shifting the said plurality of switches of the said second electro-magnet upon the entry of a car or train into the said block or section, a second signal, means for displaying said 50 second signal when the plurality of switches are shifted and for discontinuing the display of the first said signal, a third signal, means responsive to the entry of a car or train into the block or section in advance of the first block or section for energizing the said second electro-magnet and de-energizing the said third electro-magnet and means responsive to such altered conditions of said 55 second and third electro-magnets for displaying said third signal.
13. In a railway block signaling system, an insulated rail or rail section in the track rails at each block signaling station on each side of the 60 track, an incomplete electric circuit connecting the said insulated rail sections including an electro-magnet, a second electro-magnet and a plurality of switches therefor, being mechanically latched in one of their operating positions, a third electro-magnet, a signal, means controlled by said 65 second and third electro-magnets for governing the display of the said signal, said first electro-magnet adapted for shifting the said plurality of switches of the said second electro-magnet upon the entry of a car or train into the said block or section, a second signal, means for displaying said second signal when the plurality of switches are shifted and for discontinuing the display of the first said signal, a third signal, means responsive to the entry of a car or train into the block or section in advance of the first block or section for energizing the said second electro-magnet and de-energizing the said third electro-magnet and means responsive to such altered conditions of said 70 second and third electro-magnets for displaying said third signal.
14. In a railway block signaling system comprising similar signaling apparatus at each of a plurality of separate stations, said apparatus at one station comprising an insulated rail or rail section in the track rail on each side of the track, an incomplete electric circuit for the said insulated rail sections including an electro-magnet, the said insulated rail sections being adapted 75 to complete the said circuit through the wheels and axles of a car upon the entry of a car or train into the block, a switch controlled by the said electro-magnet, a second electro-magnet and a plurality of switches controlled thereby, mechanical means associated with the said second switch for controlling the said plurality of switches, a plurality of signals, and means at said one station for displaying one or another of said signals controlled by said second electro-magnet and means for controlling the said second electro-magnet including the switches of the first and second electro-magnets at another station.
15. In a railway block signaling system comprising similar signaling apparatus at each of a plurality of separate stations, said apparatus at one station comprising an insulated rail or rail section in the track rail on each side of the track, an incomplete electric circuit for the said insulated rail sections including an electro-magnet, the said insulated rail sections being adapted to complete the said circuit through the wheels and axles of a car upon the entry of a car or train into the block, a switch controlled by the said electro-magnet, a second electro-magnet and a plurality of switches controlled thereby, mechanical means associated with the said second switch for controlling the said plurality of switches, a plurality of signals, a third electro-magnet controlled by one of said plurality of switches at the station in advance of the first mentioned station and means at the first mentioned station for displaying one or another of said signals controlled by said second and third electro-magnets, and means for controlling the said second electro-magnet including the switches of the said first and second electro-magnets at the said second station.
16. In a signaling system for a block or section of a railway, which comprises a vehicle controlled circuit, an electro-magnet controlled by said circuit, a second electro-magnet, a switch therefore normally mechanically latched in its operated position, a third electro-magnet and a switch controlled thereby, a signal, means controlled by the said switches for governing the display of the said signal, and means controlled by the first said electro-magnet for releasing the mechanical latch to permit the first said switch to be moved from its operated position

upon the entry of a vehicle into the said block or section to discontinue the control of the said signal, and means responsive to the vehicle leaving the said block or section for controlling the 5 said second and third electro-magnets.

17. In a signaling system for a block or section of a railway, which comprises a vehicle controlled circuit, an electro-magnet controlled by said circuit, a second electro-magnet, a switch therefor normally mechanically latched in its operated position, a third electro-magnet normally energized, a second switch normally maintained in its operated position by the said third electro-magnet, a signal, means controlled by the first said switch for governing the display of the said second signal, and means transientsly controlled by the first said electro-magnet for releasing the mechanical latch to permit the first said switch to be moved from its operated position upon the entry of a vehicle into the said block or section to discontinue the control of the first said signal and to establish the control of the said second signal, and means responsive to the vehicle leaving the said block or section for temporarily energizing the said second electro-magnet and de-energizing the said third electro-magnet. 10

18. In a signaling system for a block or section of a railway, a vehicle controlled circuit, a normally de-energized electro-magnet controlled by said circuit, a second normally de-energized electro-magnet, a switch operated thereby and normally mechanically locked in its operated position, a third electro-magnet normally energized and a second switch normally maintained in its operated position by the said third electro-magnet, a "proceed" signal lamp, a circuit for the said "proceed" signal lamp and energized only when each of the said switches are in their operated positions to establish the display of the said "proceed" signal, and means controlled by the first said electro-magnet for releasing the mechanical lock to permit the first said switch to be moved from its operated position upon the entry of a vehicle into the said block or section to deenergize the said circuit including the signal lamp and thereby discontinue the said "proceed" signal, and means responsive to the vehicle leaving the said block or section for temporarily energizing the said second electro-magnet and de-energizing the said third electro-magnet. 15

19. In a signaling system for a block or section of a railway, which comprises a vehicle controlled circuit, an electro-magnet controlled by said circuit, a second electro-magnet, a switch therefor normally mechanically latched in its operated position, a third electro-magnet and a switch controlled thereby, a signal, means controlled by the said switches for governing the display of the said signal, a second signal, means controlled by the first said switch for governing the display of the said second signal, and means controlled by the first said electro-magnet for releasing the mechanical latch to permit the first said switch to be moved from its operated position upon the entry of a vehicle into the said block or section to discontinue the control of the first said signal and to establish the control of the said second signal, and means responsive to the vehicle leaving the said block or section for operating the said second electro-magnet to discontinue the said second signal, and means responsive to the vehicle leaving the said block or section to operate the third electro-magnet to withhold the establishment of the first mentioned signal. 20

20. In a signaling system for a block or section of a railway which comprises a vehicle controlled

circuit, an electro-magnet controlled by said circuit, a second electro-magnet, a switch therefor normally mechanically latched in its operated position, a third electro-magnet normally energized, a second switch normally maintained in its operated position by the said third electro-magnet, a signal, means jointly controlled by the said switches for governing the display of said signal, a second signal, means controlled by the first said switch for governing the display of the said second signal, and means transientsly controlled by the first said electro-magnet for releasing the mechanical latch to permit the first said switch to be moved from its operated position upon the entry of a vehicle into the said block or section to discontinue the control of the first said signal and to establish the control of the said second signal, and means responsive to the vehicle leaving the said block or section for temporarily energizing the said second electro-magnet and de-energizing the said third electro-magnet. 25

21. In a signaling system for a block or section of a railway, a vehicle controlled circuit, a normally de-energized electro-magnet controlled by said circuit, a second normally de-energized electro-magnet, a switch operated thereby and normally mechanically locked in its operated position, a third electro-magnet normally energized and a second switch normally maintained in its operated position only when the said third electro-magnet is energized, a "proceed" signal lamp, a circuit for the said "proceed" signal lamp and energized only when each of the said switches are in their operated positions to establish the display of the said "proceed" signal, a "stop" signal lamp, a circuit for the said "stop" signal lamp and energized only when the first said switch is moved from its operated position to establish the display of the said "stop" signal, and means controlled by the first said electro-magnet for releasing the mechanical lock to permit the first said switch to be moved from its operated position upon the entry of a vehicle into the said block or section to de-energize the said circuit including the said "proceed" signal lamp and to energize the circuit including the said "stop" signal lamp, and means responsive to the vehicle leaving the said block or section to energize the said second electro-magnet and to de-energize the said third electro-magnet. 30

22. In a signaling system for a section of a railway divided into a plurality of successive blocks, similar signaling apparatus for each of the separate blocks, the apparatus for one of the said blocks comprising a vehicle controlled circuit, an electro-magnet controlled by said circuit, a second electro-magnet, a switch therefor normally mechanically latched in its operated position, a third electro-magnet and a switch controlled thereby, a signal, means jointly controlled by the said switches for governing the display of the said signal, a second signal, means controlled by the first said switch for governing the display of the said signal, means controlled by the first said electro-magnet for releasing the mechanical latch to permit the first said switch to be moved from its operated position upon the entry of a vehicle into the said one block to discontinue the control of the first said signal and to establish the control of the said second signal, and means responsive to the entry of a vehicle into the block in advance of the first said block for energizing the said second electro-magnet to restore the first said switch to its normal condition and discontinue the control of the said second signal. 35

- and means controlling the operation of the said third electro-magnet in response to the occupied or unoccupied signaled condition of the said block in advance of the first mentioned block.
23. In a signaling system for a section of a railway divided into a plurality of successive blocks, similar signaling apparatus for each of the separate blocks, the apparatus for one of the said blocks comprising a vehicle controlled circuit, an electro-magnet controlled by said circuit, a second electro-magnet, a switch therefor normally mechanically latched in its operated position, a third electro-magnet normally energized, a switch normally maintained in its operated position by the said third electro-magnet, a signal, means controlled by the said switches for governing the display of the said signal, a second signal, means controlled by the first said switch for governing the display of the said second signal, means controlled by the first said electro-magnet for releasing the mechanical latch to permit the first said switch to be moved from its operated position upon the entry of a vehicle into the said one block to discontinue the control of the first said signal and to establish the control of the said second signal, and means responsive to the entry of a vehicle into the block in advance of the first said block for temporarily energizing the said second electro-magnet to restore the first said switch to its normal condition and discontinue the control of the said second signal, and means responsive to the occupied condition of the said block in advance of the said first block to de-energize the said third electro-magnet.
24. In a signaling system for a section of a railway divided into a plurality of successive blocks, similar signaling apparatus for each of the separate blocks, the apparatus for one of the said blocks comprising a vehicle controlled circuit, a normally de-energized electro-magnet controlled by said circuit, a second normally de-energized electro-magnet, a switch operated thereby and normally mechanically locked in its operated position, a third electro-magnet normally energized and a second switch normally maintained in its operated position by the said third electro-magnet, a "proceed" signal lamp, a circuit for the said "proceed" signal lamp and energized when each of the said switches are in their operated positions to establish the display of the said "proceed" signal, a "stop" signal lamp, a circuit for the said "stop" signal lamp and energized only when the first said switch is moved from its operated position to establish the display of the said "stop" signal, means controlled by the first said electro-magnet for releasing the mechanical latch to permit the first said switch to be moved from its operated position upon the entry of a vehicle into the said one block to de-energize said circuit including the said "proceed" signal lamp and to energize the circuit including the said "stop" signal, and means responsive to the entry of a vehicle into the block in advance of the first said block for temporarily energizing the said second electro-magnet to restore the first said switch to its normal condition and de-energize the circuit including the said "stop" signal, and means effective only when the "stop" signal is displayed for the said block in advance of the first block, to de-energize the said third electro-magnet and withhold operation of the said "proceed" signal.
25. In a signaling system, comprising similar signaling apparatus at each of a plurality of separate stations, said apparatus at one station comprising a vehicle controlled circuit, an electro-magnet controlled by the said circuit, a switch controlled by the said electro-magnet, a second electro-magnet and a second switch controlled thereby, means associated with the first said switch for controlling the said second switch, a signal, a third electro-magnet and a third switch controlled thereby, said third switch in normal condition co-operating with said second switch to display said signal, said second switch operable in response to control of the first switch by the first electro-magnet upon the entry of a car or train into said block or section to discontinue co-operation between said second and third switches to discontinue display of said signal, a second signal brought to display in response to said operation of said second switch, a third signal, and means responsive to entry of a car or train into a block or section in advance of first named block or section, controlling said second electro-magnet to restore said second switch to its previous condition, and changing said third switch from its normal condition, and means responsive to the restoration of said second switch to its previous condition and alteration from normal condition of said third switch causing display of said third signal.
26. In a signaling system, comprising similar signaling apparatus at each of a plurality of separate stations, said apparatus at one station comprising a vehicle controlled circuit, an electro-magnet controlled by the said circuit, a switch controlled by the said electro-magnet, a second electro-magnet and a plurality of switches controlled thereby, means associated with the first said switch for controlling the said plurality of switches, a third electro-magnet controlled by one of said plurality of switches at another station, and means at said one station for displaying one or another of said signals controlled by said second and third electro-magnets, and means for controlling the said second electro-magnet including the switches of the said first and second electro-magnets at the said another station, said first electro-magnet being controlled only by the transient movement of a car or vehicle at the same station.
27. The combination with a vehicle controlled circuit, operating means controlled thereby, of signaling apparatus at a station comprising a mechanically locked switch controlled by the said operating means, means co-operating with the said mechanically locked switch for giving a plurality of signal indications, an electro-magnet for controlling the second mentioned means, the said mechanically locked switch controlled by the said operating means to change the signal indication, and a mechanically locked switch at another station responsive to a vehicle for controlling the said electro-magnet and the first said mechanically locked switch to give another signal indication.
28. The combination with a vehicle controlled circuit, operating means controlled thereby, of signaling apparatus at a station comprising a mechanically locked switch controlled by the said operating means, a normally de-energized electromagnet for actuating the said mechanically locked switch to a normal condition, the said mechanically locked switch controlled by the said operating means to give a signal indication, and a mechanically locked switch at another station actuated in response to an operation of its associate vehicle controlled circuit, to temporarily energize the said normally de-energized electro-

magnet to restore the first said mechanical locked switch at the said one station to a normal condition to discontinue the said signal.

29. The combination with a vehicle controlled circuit, operating means controlled thereby, of signaling apparatus at one station comprising a mechanically locked switch controlled by the said operating means, means co-operating with the said mechanically locked switch for giving a plurality of signal indications, a normally de-energized electro-magnet for actuating the said mechanically locked switch to a normal condition, a normally energized electro-magnet for controlling the said means, the said means normally co-operating with the normal condition of the said mechanical locked switch to give one of said signal indications, the said mechanically locked switch controlled by the said operating means to give a different indication, and a mechanically locked switch at another station actuated in response to an operation of its associate vehicle controlled circuit to temporarily energize the said normally de-energized electro-magnet to restore the mechanically locked switch at the said one station to normal, and means responsive to the altered condition of the mechanically locked switch at said another station to de-energize the said normally energized electro-magnet, and means at said one station responsive to the normal condition of its mechanical locked switch and altered condition of the said normally energized electro-magnet to give another signal indication.

30. The combination with a vehicle controlled circuit, operating means controlled thereby, of signaling apparatus at one station comprising a mechanically locked switch controlled by the said operating means, means co-operating with the said mechanically locked switch for giving a plurality of signal indications, a normally de-energized electro-magnet for actuating the said mechanically locked switch to a normal condition, a normally energized electro-magnet for controlling the said means, the said means normally co-operating with the normal condition of the said me-

chanical locked switch to give one of said signal indications, the said mechanically locked switch controlled by the said operating means to give a different indication, and a mechanically locked switch at another station actuated in response to an operation of its associate vehicle controlled circuit to temporarily energize the said normally de-energized electro-magnet to restore the mechanically locked switch at the said one station to normal, and means responsive to the altered condition of the mechanically locked switch at said another station to de-energize the said normally energized electro-magnet, and means at said one station responsive to the normal condition of its mechanical locked switch and altered condition of the said normally energized electro-magnet to give another signal indication.

31. The combination with a vehicle controlled circuit, operating means controlled thereby, of signaling apparatus at a station comprising means for giving a plurality of signal indications, a mechanically locked switch controlled by the said operating means, an electro-magnet for actuating the said mechanically locked switch to a normal condition, a second switch normally co-operating with the mechanically locked switch to affect the said means to give one signal indication, the said mechanical locked switch responsive to an operation of the vehicle controlled circuit to affect the said means to give a different indication, a switch at another station, and means responsive to an operation thereof to alter the condition of the said second switch, the said means responsive to the normal condition of said mechanically locked switch and said altered condition of the second switch to give another signal indication.

FRANK H. RICHTERKESSING.
